ATTORNEY

UNITED STATES PATENT OFFICE.

LOUIS SICKLES, OF PHILADELPHIA, PENNSYLVANIA.

DESIGN FOR A BADGE.

SPECIFICATION forming part of Design No. 34,702, dated July 2, 1901.

Application filed May 11, 1901. Serial No. 59,873. Term of patent 7 years.

To all whom it may concern:

Be it known that I, LOUIS SICKLES, a citizen of the United States of America, residing in the city and county of Philadelphia, in the 5 State of Pennsylvania, have invented and produced a new and original Design for Badges, of which the following is a specification, reference being had to the accompanying drawings, forming part thereof.

10 Figure 1 is a front view of a badge, showing my new design. Fig. 2 is a side view thereof. Fig. 3 is a back view of the same.

15 My design consists in the form or configuration of an emblematic badge, as shown in said drawings, in which the characteristic features are a ribbon-like frame or support *a*, connect-

ed at its lower end by a cross-bar *a'*, and superposed on the same is an elk's head *b* in alto-rilievo. Accessories, such as a pendant *c*, hanging from the elk's mouth, and a ring *d* at the top of the ribbon-like frame, are added, as shown. 20

I claim—

The design for a badge, substantially as herein shown and described. 25

In testimony whereof I have hereunto affixed my signature in the presence of two subscribing witnesses.

LOUIS SICKLES.

Witnesses:

LOUIS STEIN,
ANDREW V. GROUPE.
